UNITED STATES PATENT OFFICE.

THEODORE A. SEITZ, OF GRAND RAPIDS, MICHIGAN.

ELECTRIC MOTOR.

SPECIFICATION forming part of Letters Patent No. 735,160, dated August 4, 1903.

Application filed March 23, 1903. Serial No. 149,174. (No model.)

To all whom it may concern.

Be it known that I, THEODORE A. SEITZ, a citizen of the United States, residing at Grand Rapids, in the county of Kent and State of Michigan, have invented certain new and useful Improvements in Electric Motors; and I do hereby declare the following to be a full, clear, and exact description of the invention, such as will enable others skilled in the art to 5 which it appertains to make and use the same.

My invention relates to improvements in electric motors, and more particularly to such motors adapted for carving-machines and analogous devices; and its object is to provide 15 a compact and effective electric motor, to provide the same with means for both angular and longitudinal adjustment of the spindle, to provide means whereby the spindle may be readily removed and replaced without dis- 20 turbing the balance of the machine, and to provide the device with certain new and useful features, hereinafter more fully described, and particularly pointed out in the claims.

My invention consists, essentially, of an 25 electric motor mounted on a suitable support and provided with a universal-joint adjustment, whereby its axis may be adjusted angularly in any desired direction and having its armature mounted on a sleeve provided 30 with a clamp for holding the spindle, a case surrounding the armature and having inwardly-projecting field-magnets and bearings at each end for the spindle, and a spindle longitudinally adjustable in the sleeve, and 35 means for clamping the spindle in place within the sleeve, consisting of a longitudinal slot in the sleeve and a band and set-screw surrounding the slotted portion of the sleeve, and in the combination and arrangement of 40 parts, as will more fully appear by reference to the accompanying drawings, in which—

Figure 1 is an enlarged vertical section of the motor, taken on the line 1 1 of Fig. 3; Fig. 2, a rear elevation of the device; Fig. 3, 45 a plan view of the same; Fig. 4, an enlarged detail of the brushes; Fig. 5, a detail of the clamping means for holding the spindle; Fig. 6, a detail of the means for clamping the stem of the universal joint, and Fig. 7 a detail in 50 transverse section of one of the brush-holders.

Like letters refer to like parts in all of the figures.

A represents any suitable column or stand- 55 ard, slotted vertically at one side and provided with lugs A' opposite the slot and a binding-screw A'', extending through the lugs.

B is a ball-socket to receive the ball C' on the case C and divided horizontally and provided with clamping-screws B' and a downwardly-projecting stem B'', rotative in the post A and clamped therein by means of the screw A'.

C is a cylindrical case for the motor, pro- 65 vided with a rearwardly-projecting ball C'', inserted in the socket B and movable in all directions therein, whereby the axis of the case is universally adjustable. Said case is also provided with inwardly-projecting field- 70 magnets C', provided with pole-pieces or shoes P, detachably secured thereto, and field-coils P'.

D represents removable heads to the case having axial bosses D', in which bosses are inserted journal-bearings D'' for the spindle 75 F. Surrounding the spindle is a sleeve G, provided with bearings G' at each end, whereby the sleeve is retained in the axis of the case when the spindle is removed. This sleeve is also split longitudinally at G'' and 80 surrounded by a clamping-band H, provided with a binding-screw H', whereby the spindle is adjustably secured within the sleeve. In the head D opposite the band H is a removable plug I, whereby a socket-wrench may be 85 inserted to operate the screw H' to adjust or remove the spindle. Fixed on the sleeve G is the armature F, by which the sleeve and spindle are rotated.

J is the commutator, also mounted on the 90 sleeve G.

K represents the brushes, consisting of rectangular pieces of suitable material longitudinally movable in casings L and held in contact with the commutator by springs N. Said 95 casings are provided with suitable caps M, in which caps the line-wires O, comprising the electric circuit, are secured. The casings L are also suitably mounted in insulated openings in the head D and secured in place by 100 set-screws L'.

The bearings D'' are provided with capillary lubricators E, which lubricators are inserted in openings in the under side of said

bearings and also extend through corresponding openings in the bosses D, whereby the bearings are secured in place by the lubricators.

- 5 The ball C" can be rotated in the socket B about a horizontal axis to adjust the axis of the motor and spindle at pleasure. It may also be rotated about a vertical axis to a limited extent, and when necessary the socket 10 B can be rotated about its vertical axis to any extent required. By tightening the screws B' and A" the motor will be rigidly held in whatever position it may be adjusted. By slackening the screw H' the spindle F is released 15 and may be wholly withdrawn or can be longitudinally adjusted in the sleeve, as occasion requires, and at the same time the bearings of the sleeve G will retain the same in the axis of the case. The end of the spindle, having any suitable tool attached, can thus be 20 adjusted at greater or less distance from the motor and can also be adjusted at any angle or position whatever, as occasion may require. By detaching one of the heads D the sleeve 25 and the parts supported thereon are readily removed for inspection or repairs.

Having thus fully described my invention, what I claim, and desire to secure by Letters Patent, is—

- 30 1. In a motor, longitudinally-adjustable and removable spindle, bearings for the spindle, a sleeve between the said bearings and surrounding the spindle, an armature and commutator mounted on the sleeve, and a clamp 35 to adjustably and detachably hold the spindle in the sleeve.

2. In a motor, the combination of a sleeve, bearings for the sleeve, an armature mounted on the sleeve, a spindle longitudinally adjustable in the sleeve and also detachable therefrom, and a clamp to hold the spindle in the sleeve.

3. In a motor, the combination of a case having inwardly-projecting field-magnets on 45 its interior, a detachable head to the case, a longitudinally - adjustable and removable spindle in the axis of the case, bearings for the spindle in the heads of the case, a sleeve in the axis of the case and journaled in the 50 inner ends of the spindle-bearings, an armature and commutator mounted on the sleeve, and brushes inserted in one head of the case and engaging the commutator.

4. The combination of a case, inwardly-projecting field-magnets on the case, a detachable head on the case, a spindle in the

axis of the case, bearings for the spindle in the heads of the case, a sleeve between the bearings and surrounding the spindle, and also having a longitudinal slot, a clamping-band surrounding the sleeve and provided with a screw, a removable plug in the case opposite the band, and an armature and commutator mounted on the sleeve.

5. The combination of an electric motor, 60 having a longitudinally-adjustable spindle, a case to the motor, a column to support the case, and a universal joint connecting the case and column, whereby the axis of the spindle is angularly adjustable in all directions.

6. The combination of a motor having a longitudinally-adjustable spindle, a column provided with a longitudinal slot and a clamping-screw, a socket having a downwardly-projecting stem rotative in the column and held by the screw and a case to the motor having a projection rotative in the socket.

7. The combination of a hollow column having a vertical slot in one side and lugs and 80 clamping-screw opposite the slot, a ball-socket divided horizontally and provided with clamping-screws, a stem on the socket and rotative on a vertical axis in the column, and a motor having a ball inserted in the 85 socket and adjustable therein, whereby the axis of the motor is angularly adjustable in every direction at pleasure.

8. The combination of a column, a motor-case connected to the column by a universal joint and supported thereby, a sleeve in the axis of the case, and having the armature and commutator of the motor mounted thereon, a detachable and adjustable spindle in the sleeve, and a clamp to hold the spindle.

9. In a motor, the combination of a case, detachable heads to the case, bearings in the axis of the heads, a spindle journaled in the bearings, a sleeve also journaled in the inner ends of the bearings, a clamp on the sleeve to adjustably hold the spindle, field-magnets on the interior of the case, an armature and a commutator mounted on the sleeve, and brushes detachably inserted in insulated openings in one of the heads and engaging 100 the commutator.

In testimony whereof I affix my signature in presence of two witnesses.

THEODORE A. SEITZ.
